UNITED STATES PATENT OFFICE.

WILLIAM E. MENZIES, OF IRWIN, PENNSYLVANIA, ASSIGNOR TO WESTINGHOUSE ELECTRIC & MANUFACTURING COMPANY, A CORPORATION OF PENNSYLVANIA.

GEARED LIMIT SWITCH.

Application filed September 23, 1921. Serial No. 502,605.

My invention relates to geared limit switches and it has particular relation to such devices as may be employed in connection with internal-combustion engines for isolated electric plants or the like.

My invention has for one of its objects to provide a limit switch that may be easily and conveniently adjusted for operation at a desired future time.

10 A second object of my invention is to provide a limit switch having means for indicating the period of time that must elapse before the switch is effective.

15 A further object of my invention is to provide a gear mechanism for limit switches having a relatively high ratio between the driving and the driven members and which occupies comparatively little space.

20 The details of my invention will be described in connection with the accompanying drawings, in which

25 Figure 1 is a top view of a limit switch constructed in accordance with my invention, a portion of a driving shaft and certain stationary supporting means being shown therewith.

Fig. 2 is an end view of the limit switch as viewed from the left in Fig. 1.

30 Fig. 3 is a view, in transverse section, taken on line III—III of Fig. 1.

Fig. 4 is a view, in axial section, taken on line IV—IV of Fig. 2.

35 Fig. 5 is a view of the stationary contact member of the limit switch together with a portion of its associated parts.

Fig. 6 is a diagrammatic view of circuits and apparatus of an ignition system of an internal-combustion engine with my improved limit switch applied thereto.

40 Referring to the drawings, a limit switch 1 comprises a stationary casing member 2, a rotatable casing member 3 that contains a reduction gear mechanism 4, a casing member 5, which may be adjustably secured to the stationary member 2, a driving shaft 6 that may be connected to any suitable rotatable part of an engine or similar device, a movable contact member 7 that is connected to the rotatable casing member 3 and a co-acting stationary contact member 8 that is mounted on the stationary casing member 2.

45 The stationary casing member 2 is provided with a peripheral flange 10 having suitable screw or bolt holes 11 for securing

the member 2 to any suitable stationary portion of a gas engine or similar device. The casing member 2 is, also, provided with a centrally-disposed sleeve-like projection 12 and with a circumferential opening 13 that is covered by transparent material such, for example, as glass 14. The stationary contact member 8, which may be of any suitable size and form, is here shown as rectangular in cross-section. It is mounted upon, and insulated from, the stationary casing member 2 and is electrically connected to the ignition system, as will be explained in connection with Fig. 6.

The casing member 5, which is operatively connected to one member of the reduction gear mechanism 4, is provided with a centrally-disposed sleeve-like projection 15 to be received by the sleeve-like projection 12 of the casing member 2. The member 5 is provided, also, with a screw-threaded projection 16 upon which is mounted a thumb-nut 17, whereby the members 2 and 5 may be rigidly clamped together for the purpose of preventing relative movement. A thumb-nut 18 provides a convenient means for adjusting the position of the plate member 5 and its connected parts relatively to the casing member 2 when the thumb-nut 17 has been loosened to permit such adjustment.

50 The rotatable casing member 3 is provided with an annular plate 19 which surrounds the projection 15 of plate member 5 and permits relative rotative movement of the casing member 3 and the member 5. The latter members maintain the various parts of the reduction-gear mechanism 4 in operative relation, as will be hereinafter set forth. The member 3 is provided with a central projection 20 to provide a bearing for the driving shaft 6. The casing member 3 is provided, on its periphery, with a dial 21 that is calibrated, for example, to indicate the number of hours of operation of the shaft 6 at a given rate to effect the engagement of the contact members 7 and 8 of the limit switch from any relative position to which they have been adjusted or actuated. The dial may be read through the transparent member 14.

55 Referring particularly to Figs. 3 and 4, the reduction-gear mechanism comprises duplicate units or series of pinions and gear wheels, only one of which will be described.

in detail. The shaft 6 is provided with a small pinion 22, which may be termed a "sun" pinion, that meshes with a floating-ring gear wheel 23 that may be termed a 5 "planet" gear. The gear wheel 23, in turn, meshes with a pair of internal gear wheels 24 and 25 each of which is one-half the thickness of the gear wheel 23 and the pinion 22. The gear wheels 24 and 25, which 10 are respectively secured to, and loosely mounted within, the casing member 3, are respectively provided, for example, with seventy-two and seventy-three gear teeth. A disk 26, which maintains the relative axial 15 position of the several gear wheels, is connected to the gear wheel 25 for rotation therewith.

With the gear wheels arranged as described above, one revolution of the ring 20 gear wheel 23, about the central axis of the system, advances the gear wheel 25 relatively to the gear wheel 24, a distance equivalent to the width of one tooth of the gear wheel 25. Accordingly, seventy-three revolutions of the gear wheel 23 are required to 25 rotate the gear wheel 25 through 360° . If, for example, eight revolutions of the pinion 22 are required to effect one revolution of the gear wheel 23, five hundred eighty- 30 four revolutions of the pinion 22 are required to effect a complete revolution of the gear wheel 25. Inasmuch as the disk 26 is connected to a "sun" pinion 27 of an arrangement comprising gear wheels 28, 29 35 and 30 corresponding, respectively, to gear wheels 23, 24 and 25, it will be evident that the number of revolutions of the shaft 6 required to effect a complete revolution of the last member of the train of mechanism is 40 $\frac{2}{584}$ or, approximately, a ratio of 342,000 to 1.

The second portion of the train of gear 45 mechanism is located between the disk 26 and the plate member 5, the latter being connected to the internal gear wheel 30 which is the last member of the train and which remains stationary when the member 5 is clamped by the thumb-nut 17.

50 Reference may now be had to Fig. 6, in which is illustrated the ignition system of a single-cylinder internal-combustion engine. Energy is supplied from the ungrounded side of a battery 32 through a manually-operable switch 33, an interrupter 34 and the primary winding 35 of an induction coil 36 to ground. The secondary winding 37 of the induction coil is connected in circuit with a spark plug 38, one terminal of which 55 is grounded. When the manually-operable switch 33 is closed, the ignition circuit is operative. The limit switch 1 is connected in shunt-circuit relation to the interrupter. When the contact members 7 and 8 are not 60 in engagement, as illustrated in Fig. 6, the

limit switch does not affect the operation of the system. When, however, the switch has operated to effect engagement of contact members 7 and 8, the interrupter 34 is short-circuited and the engine is brought to rest 70 because the interrupter is ineffective to make or break the circuit for the production of sparks at the spark plug 38.

In the operation of the limit switch, the shaft 6, which may be operatively connected 75 to the cam shaft 40 of an internal-combustion engine, is driven at a substantially constant speed. If it is desired to operate the engine for driving an electric generator to charge a storage battery, the length of time 80 required to charge the battery may be obtained in any desired or well known manner. For example, the specific gravity of the battery is measured by a hydrometer and the number of hours required to charge the battery 85 may be computed therefrom or secured from a table, or the hydrometer may be calibrated to read directly the number of hours required to fully charge the battery. The limit switch is then adjusted to an initial 90 position by loosening the thumb-nut 17 and rotating the plate member 5, together with the casing member 3 and the reduction-gear mechanism contained therein, until the number on the dial corresponds to the number 95 of hours computed or indicated as necessary to charge the battery. The thumb-nut 17 is then tightened to maintain the relative positions of the plate member 5 and the stationary member 2. 100

Since the gear wheel 30 is stationary, the rotation of shaft 6 and the pinion 22 effects rotation of the several members of the train, relatively to gear wheel 30, to effect the rotation of the casing member 3, the dial 105 thereon and the movable contact member 7 carried thereby. The dial indicates, at any given time, the number of hours required to complete the charging operation. When the dial indicates zero, the contact members 7 110 and 8 are in engagement and the engine is brought to rest.

115 It is to be understood that the limit switch may operate to open the ignition circuit instead of merely short-circuiting a portion thereof, as shown and described herein. It will be understood, further, that the dial of the limit switch may be calibrated in any suitable units such, for example, as the specific gravities of the battery which correspond to periods of time necessary for charging the battery. I may, also, arrange to clamp the movable casing member and the dial and the movable contact member on the adjustable portion of the casing. The 120 number of gear units may be increased if desired. These and other modifications will be apparent to those skilled in the art to which my invention appertains.

125 It will be noted that I have provided an 130

arrangement whereby the operation of a limit switch may be predetermined within definite limits by extremely simple and efficient means. A limit switch constructed in accordance with my invention provides an exceedingly high gear reduction by means of mechanism consisting of comparatively few parts and the members of which are of sufficient size to provide gear teeth of ample cross-section to provide the necessary mechanical strength. The entire device may be mounted in a very small space at a position that is convenient for observation and manual adjustment.

15 I claim as my invention:

1. The combination with a stationary member and a casing having relatively movable parts one of which is adjustably secured to said stationary member, of coacting contact members respectively carried by said stationary member and one of said casing parts, a reduction gear mechanism within said casing for operatively connecting said casing parts, means for actuating said gear mechanism, and means carried by one of said casing parts for indicating the time required to effect the engagement of said contact members from any relative position of the latter.
2. The combination with a rotatable member, a reduction gear mechanism, and a casing therefor secured to a member of said mechanism, of coacting contact members respectively connected to said casing and to a relatively movable member of said mechanism, and means for adjustably securing another member of said mechanism whereby actuation of said rotatable member effects

rotation of said casing and relative movement of said contact members.

3. The combination with a reduction gear mechanism, and a casing therefor having a plurality of parts respectively connected to members of said mechanism, of coacting contact members carried by certain of said parts and adjustable means for restraining rotation of one of said casing parts whereby relative movement between said contact members is produced.

4. The combination with a member having an opening, a second member projecting through said opening and adjustable means for preventing relative movement of said members, of a third member rotatably mounted on the second member, coacting contact members carried by said second and said third members, and a reduction gear mechanism for operatively connecting said second member and said third member.

5. The combination with a member having an opening, a second member projecting through said opening and adjustable means for preventing relative movement of said members, of a third member rotatably mounted on the second member, coacting contact members carried respectively by said second and said third members, a reduction gear mechanism supported by said third member and operatively connected to the latter member and to said second member, and an actuating member for said mechanism.

In testimony whereof, I have hereunto subscribed my name this 6th day of September 1921.

WILLIAM E. MENZIES.
